J. WOODS

DISPENSING CONTAINER

Filed May 28, 1923

Patented June 10, 1924.

1,497,255

UNITED STATES PATENT OFFICE.

JAMES WOODS, OF WEST PITTSSTON, PENNSYLVANIA.

DISPENSING CONTAINER.

Application filed May 28, 1923. Serial No. 642,134.

To all whom it may concern:

Be it known that I, JAMES Woods, a citizen of the United States of America, and a resident of West Pittston, county of 5 Luzerne, and State of Pennsylvania, have invented certain new and useful Improvements in Dispensing Containers, of which the following is a full and clear specification.

10 The object of this invention is to provide a simple apparatus for dispensing granular and other non-liquid loose materials, the idea being to avoid handling the material while dispensing it and to keep the material 15 while in the container practically safe from the entry of dust, air, germs, moisture, etc., as more fully hereinafter set forth.

In the drawing—

20 Fig. 1 is a horizontal sectional view and Fig. 2 is a partial vertical section and a side elevation of an apparatus embodying my invention;

Figs. 3, 4 and 5 are detail views of parts hereinafter described.

25 Fig. 6 is a detail view of a modification of the container-funnel;

Fig. 7 is a detail view of a modification.

Referring to the drawing by reference characters, 10 designates a common form of 30 sheet-metal keg or barrel in which loose carbide is commonly sold, and 11 is a funnel or conical ring built into the barrel and forming a permanent part thereof, a suitable screw-cap closure (not shown) being 35 usually provided for screwing into the usual inturned nipple 11'. It is the object of my invention to provide an apparatus which will support this barrel or keg in an inverted position and will permit the loose 40 carbide to be delivered in measured quantities from time to time from the exit of the funnel-top, the construction being such that all the material will run out.

The numerals 12 designate three supporting-legs which have attached to their upper ends supporting-brackets 13, each of which is provided with an upstanding ear 14 provided with an inwardly-extending lug 15. Each of these lugs 15 is adapted to engage 50 a cam-rib 16 affixed to a flexible steel band 17 whose ends are connected by a bolt 18 or otherwise to enable the band to be contracted and expanded. Riveted to the inwardly-extending supporting-flanges 13 is a depending funnel 19 whose annular flange 20 55 rests upon the aforesaid flanges 13 and

whose lower end is closed by a suitable laterally-sliding gate 21, provided with a handle 22 for operating it and pivoted at the end opposite the handle to the lower end 60 of the funnel 19. A suitable supporting-and-guide-lug 23 is attached to this gate and arranged to overhang a supporting-and-guiding-flange 24 carried by the funnel 19, one end of this flange 24 being provided 65 with a stop 25 for arresting the movement of the gate in its closing movement. The flange 24 is thickened from its outer end toward the stop-lug 25 to provide a cam surface, as shown in Fig. 4, to thereby draw the slide-gate hard against the lower end of the funnel 19 when the gate is swung to closed position.

To apply my apparatus to a container of the type described, i. e., a container in which 75 a permanent conical hopper 11 is built into the upper end of the container for pouring purposes, I first clamp the band 17 around the top end of the container; then lay an annular gasket 26 on the top of the container, around the opening; then the funnel 19, together with the legs and other attached parts, is placed over the opening in an inverted position, the lugs 14 being positioned at points between the spaced segmental cams 80 16; then, by rotating the leg structure and its funnel 19, the lugs 15 are caused to ride up the cam-ribs and thus draw the flange 20 of the funnel 19 tightly against the gasket 26; then the apparatus may be turned 85 right-side-up on its legs, when it is ready for operation. It will be observed that with my apparatus I can make use of all carbide containers on the market and that the use of my device avoids all the inconveniences 90 and dangers of scooping out the carbide by hand or pouring it out; and, further, my apparatus keeps the carbide well sealed and therefore in prime condition.

I have described my container as being 100 especially useful in dispensing carbide, but it will be understood that it may be used with advantage for dispensing any loose material, especially those materials which need to be kept free from air, moisture or germs 105 or are dangerous to handle.

The funnel-ring 11 fills in the annular space between the screw-nipple 11' and the body of the barrel in order that all the material may be run out of the barrel. I prefer 110 building this ring permanently in the container, as shown in Fig. 2, but in those cases

where this ring is not built into the container, I may insert a removable sectional ring such, for instance, as shown in Fig. 6, which consists of three or more segments 5 adapted to be normally expanded slightly by means of coil-springs 11², to the end that all the material may run out of the barrel. Instead of the overhanging lug 23, I may use a roller 23', as shown in Fig. 7, adapted 10 to run on the flange 24 for the purpose of reducing friction. Other details of construction may be varied, as is obvious, without departing from the spirit of my invention.

15 What I claim is:

1. In a dispensing apparatus, a container having a discharge-opening in its lower end, a supporting structure embodying a discharge-funnel adapted to fit over said open 20 end, a gate for this funnel, said supporting structure embodying a plurality of cam-lugs, and an expansible and contractible band clamped around the container and carrying cam ribs adapted to engage said 25 cam-lugs, for the purpose set forth.
2. A dispensing apparatus consisting of a vertical container having a discharge-opening at its lower end, a discharge-fun-

nel adapted to support said container and means for supporting the funnel, a gasket 30 arranged between the container and the funnel, and means for removably fastening the container on the funnel consisting of cam-lugs on the supporting means and spaced cam-ribs carried by the container, 35 said cam-ribs being detachably connected to the container.

3. In a dispensing apparatus, a vertically-arranged container having a discharge-opening at its lower end, this opening being provided with an annular flange extending into the container, a funnel-ring detachably mounted within the container between said flange and the body of the container to facilitate the discharge of material from 45 the container, a supporting structure supporting a discharge-funnel which in turn supports the container, and means for detachably clamping the container down on the funnel.

In testimony whereof I hereunto affix my signature.

JAMES WOODS.

Witness:

THOMAS G. EVANS.
